ELECTRIC HOIST AND WINCH CONTROL

Kurt Mahanke, Pittsburgh, Pa., assignor to Westinghouse Electric Corporation, East Pittsburgh, Pa., a corporation of Pennsylvania

Application November 29, 1947, Serial No. 788,951

7 Claims. (Cl. 318—261)

1

My invention relates to electric controls for hoists, winches and the like devices for operating a rope or cable and deals particularly, though not exclusively, with marine deck equipment of this kind. More specifically, my invention is concerned with rope-operating equipment which, when at rest, is locked by latching bolts, ratchet-and-pawl devices, clutches or other locking means that must be released before the equipment can operate in the lowering or pay-out direction.

There are electric systems for controlling mechanically locked boom topping winches so that the pawl of a locking ratchet is electromagnetically released when the operator actuates the appertaining master control means in the proper manner. In these systems, the release of the ratchet, previous to lowering, occurs during an initial interval in which the winch motor is energized for hoisting to relieve the load on the ratchet mechanism while immediately thereafter the motor is reversed or reconnected for lowering. Two reversing contactors and a number of associated control relays are provided in the known system in order to perform the just-mentioned switching and reversing operations.

It is an object of my invention to provide control systems for mechanically latched winches that secure a reliable unlatching performance for hoisting as well as lowering with the aid of control means of utmost simplicity, with a reduced number of component parts, and under correspondingly reduced space requirements as compared with the above-mentioned systems heretofore available for this type of equipment.

Another object of my invention, relative to the foregoing, is to provide latch-releasing controls that are economically applicable for marine deck winches, such as boat winches, relatively small load capacity, operating with correspondingly small electric motors.

These and other objects as well as the means provided by the invention for achieving them will be apparent from the following description of the embodiments illustrated in the drawing.

Figs. 1 and 2 show two different modifications of an electric control system for a boom topping winch, both figures representing schematically the electric circuit diagram in conjunction with parts of the winch structure essential for the invention; and

Fig. 3 shows schematically a relay of the kind employed in the embodiments of Figs. 1 and 2.

In both embodiments, as illustrated, the structure of a boom topping winch as a whole is denoted by A, the appertaining electric motor for

2

lifting and lowering the boom is denoted by M, a control contactor by B, an overload relay by C, a timing relay by D, and the appertaining master controller by E. Most of the reference numerals applied to Fig. 2 are the same as those used in Fig. 1 for corresponding elements, except that the prefix 1 or 10 is added to the respective numerals of Fig. 2. For instance, the parts denoted by 3 and 10 in Fig. 1 correspond to those denoted by 103 and 110, respectively, in Fig. 2. Consequently, to a large extent, the following description of Fig. 1 is also applicable to Fig. 2.

Referring to the control system of Fig. 1, the boom 1 of the winch structure A is lifted and lowered by means of a cable or rope which is wound up on a winch drum 2. A ratchet gear 3 is firmly attached to the drum 2 or the appertaining drum shaft and cooperates with a latching pawl 4 which is spring or gravity biased into engagement with the ratchet teeth in order to normally prevent lowering of the boom 1. A solenoid 5 serves to release the pawl 4 in opposition to its spring bias. The winch drum is equipped with a spring-set friction brake 6 which is released when the appertaining magnet coil 7 is energized.

The armature 8 of the motor M is mechanically connected with drum 2 by a suitable transmission or gearing here schematically represented by a broken line denoted by 9. The motor has two field windings 10 and 11. Motor armature and field windings receive excitation from the mains X and Y of a suitable direct-current source under control by the above-mentioned relays B, C and D and subject to the operator-controlled adjustment of the master controller E.

The control relay B has a main coil 12 and a lockout coil 13. The main coil 12 controls four contacts 14, 15, 16 and 17 and receives excitation from the mains X and Y in a manner described below. The lockout coil 13 is permanently connected across the motor armature 8. Coil 13, even if energized, is ineffective to change the condition of relay B after the relay is picked up by the main coil 12, that is, coil 13 is effective to lock only when it is sufficiently energized after relay B has dropped out. Then the energized coil 13 secures sufficient contact pressure at contact 14 and prevents the relay B from again picking up as long as the regenerative armature voltage of motor M remains above a given minimum value. In order to secure this lockout action, the relay B in its actual design may have an armature of the type denoted by 20 in Fig. 3. When the main coil 12, according to Fig. 3, is

energized, it moves the armature 20 and closes contact 15 (as well as contacts 16 and 17 which are not shown in Fig. 3), while opening the contact 14. As a result, the airgap between armature 20 and the core of coil 13 becomes so large that the subsequent energization of coil 13 produces no armature movement. However, when thereafter the main coil 12 is deenergized so that armature 20 drops back to the illustrated position, the coil 13, when energized, holds contact 14 safely closed and locks the relay in the dropped-off position as long as the energization of coil 13 remains above the above-mentioned minimum.

The overload relay C has a main coil 18 to be traversed by the motor load current and is equipped with a lockout coil 19. Contact 21 of relay C is opened only when the load current in coil 18 exceeds a predetermined maximum value. The performance of the lockout coil 19 is similar to that of coil 13 of contactor B as discussed in conjunction with the schematic illustration of Fig. 3.

The timing relay D has a main coil 22 and a short-circuited winding 23. When coil 22 is energized, the appertaining relay contacts 24 and 25 close immediately, while, after deenergization of coil 22, a given timing interval due to the effect of the short-circuited winding 23, elapses before the contacts 24 and 25 drop into open position.

The master controller E is shown as a drum type switch. The handle, to be actuated by the operator, is denoted by 26. This handle as well as the drum contactor are normally held in the "off" position by means of biasing springs 27. The master controller has a "hoist" position and a "lower" position and must be held by the operator in one of these positions as long as the winch is to operate. The master controller has a number of stationary contact fingers or brushes to cooperate with movable contact segments denoted by 28, 29 and 31 to 37. Three resistors appertaining to the control system are denoted by 28, 39 and 41.

The system of Fig. 1 operates in the following manner: When the master controller E, by actuation of its handle 26, is moved from "off" to "hoist" position, it passes through an intermediate position in which the contact segments 29, 31 and 33 prepare the respective circuit connections. When the "hoist" position is reached, the main coil of relay B is energized in the circuit:

X-35-12-21-Y (1)

Relay B picks up. Its contact 15 energizes the brake coil 7 in parallel to the motor field winding 10 in the circuit:

so that brake 6 is released. Coil 22 of timing relay D is energized in the circuit:

X-37-22-Y (3)

Relay D picks up and, at contact 25, energizes the solenoid 5 so that the ratchet pawl 4 is released. Motor armature 8 and field winding 11 are now energized in the circuit:

X-29-8-11-39-31-16-18-Y (4)

Consequently, motor M operates in the hoist direction.

When the master controller is released and moves back to the illustrated "off" position, relay

B drops out and applies the friction brake 6 by deenergizing the appertaining coil 1. Coil 22 of timing relay D is also deenergized, but this relay drops out only after the elapse of its timing interval. The interval is long enough to permit the friction brake 6 to stop or substantially retard the winch. Only a short interval is needed for this purpose because the hoisting load is then also effective to retard the winch. Consequently, when the timing relay D deenergizes the coil 5 and permits the pawl 4 to drop into the ratchet, the winch is already at rest or its speed is sufficiently reduced to avoid a jarring stop.

For performing lowering operations, the master controller E must first be moved to the "hoist" position and then quickly moved through the "off" position to the "lower" position. Any other way of operating the master controller will not result in lowering performance because the release of ratchet pawl 4 and brake 6 as well as the operation of the motor M depend upon picking up of the timing relay D, and the circuit conditions for causing relay D to pick up exist only in the "hoist" position of the master controller.

When the lowering performance is properly initiated by moving the master controller temporarily to hoist position, the brake and pawl are released and the motor M is started in the hoist direction in the same manner as described in the foregoing. The short winch movement in the hoist direction relieves the load and friction on the pawl and hence prepares proper conditions for the pawl release. When the master controller is rapidly switched over to "lower" position, coil 22 of timing relay D becomes temporarily deenergized due to the temporary opening of contact 11, but the relay D remains picked up during the subsequent timing interval. This interval is long enough to be still running when the master controller reaches "lower" position. Then, coil 12 of relay B becomes reenergized in the circuit

X-36-24-12-21-Y (5)

Consequently, relay B recloses the armature and field circuits of the motor which, in the meantime, has been reconnected for reversed operation, and also closes at contact 17 the circuit for coil 22 in timing relay D. As a result, this relay remains picked up during the entire switching-over performance as well as thereafter, so that the coil 5 remains energized and the pawl 4 lifted out of the ratchet 3.

As mentioned, the motor M is now connected for reverse operation. Its armature 8 is now energized in series with resistor 38 in the circuit:

Field winding 11 and resistor 39 are now series connected across the armature 8 and resistor 38. That is, the field winding 11 of motor M, which during hoisting performance acts as a series field winding, is now shunt connected and its circuit has a properly calibrated resistance to secure the desired speed limiting lowering characteristic. In contrast thereto, the field winding 10 is shunt connected to the motor armature during hoisting as well as lowering. It serves mainly as a speed-limiting winding and may be omitted without otherwise affecting the operation of the system.

When the master controller is returned to "off" position, the brake 6 is set and relay B drops off immediately, while the timing relay D remains

picked up during its timing interval. As soon as relay B drops off, a dynamic braking circuit,

8-11-14-38-28-8 (7)

is effective together with brake 6 to stop the winch before the timing interval of relay D elapses and hence before the pawl 4 is permitted to drop into the ratchet 3. During the dynamic braking period, the lockout coil 13 of contactor B is energized by regenerative voltage from armature 8 and prevents the opening of the dynamic braking circuit (7) before the motor armature has reached sufficiently low speed.

It will be recognized that in this example the operation of the dynamic braking circuit is relied upon only for stopping the winch at the end of a lowering performance, i. e., when the winch load tends to accelerate rather than to retard the winch.

If during a hoisting or lowering performance an excessive overload occurs, the main coil 18 of relay C becomes sufficiently energized to open the contact 21. This has the effect of opening the coil circuit (1) of relay B. As a result, the brake coil 7 is deenergized at contact 15 (during lowering performance the coil 22 of relay D is also deenergized for a subsequent setting of the ratchet pawl 4) and the motor armature and field circuits become deenergized due to the opening of contact 16, so that the winch is stopped. The lockout coil 19 then prevents the overload relay C from dropping out until the master controller is first moved back to "off" position. In this manner, the occurrence of pumping action, i. e., an alternate picking up and dropping out of relays B and C under excessive overloads is safely prevented.

The control system shown in Fig. 2 is similar to that of Fig. 1 in that the master controller must be operated for lowering by placing it temporarily into "hoist" position and then switching it through the "off" position to the "lower" position as described in the foregoing. The system according to Fig. 2 differs from that of Fig. 1 essentially in the provision of different motor connections so that the lowering performance, which according to Fig. 1 occurs under a "dynamic lowering" characteristic, is effected as a "shunted armature lowering." This difference in the motor energizing circuits requires a somewhat different arrangement of the master controller segments which in Fig. 2 are denoted by 136, 137 and 146 through 153, respectively. The resistors appertaining to the motor circuit of Fig. 2 are denoted by 142 through 145, respectively.

When the winch system according to Fig. 2 is set for hoisting, the motor armature 108 and main field winding 111 are energized in the circuit

X-148-108-143-146-111-116-118-Y (8)

while resistors 144 and 145 are series connected with each other in shunt relation to armature 108:

108-144-145-150-108 (9)

Auxiliary field winding 110 is separately excited in the circuit:

X-152-110-116-118-Y (10)

Aside from the just-mentioned difference in the motor energizing circuits and the corresponding difference in speed-torque characteristic, the system of Fig. 2 has the same small number of component elements and secures also the above-mentioned functions and advantages.

It will thus be seen that the particular design and operating characteristic of the motor armature and field circuits is not essential to the invention and can be modified in various ways without departing from the essential features.

While I have illustrated a master control means designed as a drum type contactor, it is obvious that other forms of known and available master control means may be used instead. For instance, the master control means may comprise two spring biased push button contacts, one for operating the motor in the hoist direction and the other for operating in the lowering direction, the "off" position being established when both push buttons are released. The individual relays, contactors and circuit connections can also be modified in various ways. It will be recognized, therefore, that the invention permits being carried out in a manner different from the embodiments specifically illustrated and described in this disclosure, without departing from the essence of the invention and within the scope of its essential features as set forth in the claims annexed hereto.

I claim as my invention:

1. A winch control system, comprising winch locking means, a winch motor, operator-actuable master control means normally in "off" position and selectively adjustable to "hoist" and "lower" positions respectively, a current supply circuit attached to said motor and connected with said master control means to operate in different directions when said master control means is in "hoist" and "lower" positions respectively, a contactor having a coil and contact means disposed in said circuit for completing said circuit only when said coil is energized, said master control means having a first contact and a second contact individually connected with said coil for energizing said coil only when said control means is in hoist and lower positions respectively, a delayed drop-out relay connected with said locking means for releasing the latter only when said relay is in picked-up condition and connected with said second contact and with said coil to permit said coil to be energized through said second contact when said relay is in picked-up condition only, said relay having a pick-up coil connected with said master control means and with said contactor so as to be energized through said master control means when the latter is in hoist position only and through said contactor when said contactor coil is energized.

2. A winch control system, comprising winch locking means, a winch motor, operator-actuable master control means normally in "off" position and selectively adjustable to "hoist" and "lower" positions respectively, a current supply circuit attached to said motor and connected with said master control means to operate in different directions when said master control means is in "hoist" and "lower" positions respectively, a contactor having a coil and contact means disposed in said circuit for completing said circuit only when said coil is energized, said master control means having a first contact closed only in "hoist" position and a second contact closed only in "lower" position, a delayed drop-out relay having a coil circuit connected to said first contact to pick-up only when said master control means is in "hoist" position and having a relay contact closed only when said relay is in picked-up condition, a contactor having a coil connected to said relay contact and to said second contact to be energized when said relay is in picked-up condition

while said master control means is in "lower" position, said contactor having a holding contact connected with said relay coil circuit for holding said relay picked up when said contactor coil is energized, said contactor being connected with said current supply circuit for controlling said motor to permit its operation only when said contactor coil is energized, and said relay being connected with said locking means for releasing it when said relay is in picked-up condition.

3. A winch control system, comprising winch locking means, a winch motor, operator-actuable master control means normally in "off" position and selectively adjustable to "hoist" and "lower" positions respectively, a contactor having a coil circuit controlled by said master control means to be energized when said control means is in one of said "hoist" and "lower" positions and having contact means controlled by said coil circuit, said master control means and said contact means being connected with said motor for operating said motor, when said coil circuit is energized, in different directions corresponding to the "hoist" and "lower" positions respectively of said master control means, a delayed drop-out relay connected to said locking means for releasing the latter when said relay is in picked-up condition, said relay having a pick-up coil connected with said master control means so as to be placed into pick-up condition only when said master control means is adjusted into "hoist" position, and a holding circuit associated with said pick-up coil and controlled by said contactors for thereafter holding said relay picked up as long as said contactor coil circuit is energized, the delay interval of said relay being rated to permit switching said master control means from "hoist" to "lower" position during said interval in order to then maintain said locking means continuously released.

4. A winch control system, comprising winch locking means, a winch motor, operator-actuable master control means normally in "off" position and selectively adjustable to "hoist" and "lower" positions respectively, a contactor having a coil circuit controlled by said master control means to be energized when said control means is in one of said "hoist" and "lower" positions and having contact means controlled by said coil circuit, said master control means and said contact means being connected with said motor for operating said motor, when said coil circuit is energized, in different directions corresponding to the "hoist" and "lower" positions respectively of said master control means, a delayed drop-out relay connected to said locking means for releasing the latter when said relay is in picked-up condition, said relay having a pick-up coil connected with said master control means so as to be placed into pick-up condition only when said master control means is adjusted into "hoist" position, a holding circuit associated with said pick-up coil and controlled by said contactor for thereafter holding said relay picked up as long as said contactor coil circuit is energized, and braking means associated with said motor and connected to said contactor to be controlled by the latter to retard said motor during the delay interval of said relay so that, when said master control means is switched to "off" position, said motor is subjected to braking before said relay permits said locking means to set.

5. A winch control system, comprising winch locking means, a winch motor, operator-actuable master control means normally in "off" position

and selectively adjustable to "hoist" and "lower" positions respectively, a contactor having a coil circuit controlled by said master control means to be energized when said control means is in one of said "hoist" and "lower" positions and having contact means controlled by said coil circuit, said master control means and said contact means being connected with said motor for operating said motor, when said coil circuit is energized, in different directions corresponding to the "hoist" and "lower" positions respectively of said master control means, a delayed drop-out relay connected to said locking means for releasing the latter when said relay is in picked-up condition, said relay having a pick-up coil connected with said master control means so as to be placed into pick-up condition only when said master control means is adjusted into "hoist" position, a holding circuit associated with said pick-up coil and controlled by said contactor for thereafter holding said relay picked up as long as said contactor coil circuit is energized, and braking means associated with said motor and connected to said contactor to be controlled by the latter to retard said motor during the delay interval of said relay, braking means associated with said motor and controlled by said contactor to be effective when said contactor coil circuit is deenergized, and a lock-out coil magnetically associated with said contactor and connected across said motor for preventing said contactor from picking up regardless of the condition of said contactor coil circuit as long as said lock-out coil, during the braking period, is sufficiently excited by regenerative voltage from said motor.

6. A winch control system, comprising winch locking means, a winch motor, operator-actuable master control means normally in "off" position and selectively adjustable to "hoist" and "lower" positions respectively, a contactor having a coil circuit controlled by said master control means to be energized when said control means is in one of said "hoist" and "lower" positions and having contact means controlled by said coil circuit, said master control means and said contact means being connected with said motor for operating said motor, when said coil circuit is energized, in different directions corresponding to the "hoist" and "lower" positions respectively of said master control means, a delayed drop-out relay connected to said locking means for releasing the latter when said relay is in picked-up condition, said relay having a pick-up coil connected with said master control means so as to be placed into pick-up condition only when said master control means is adjusted into "hoist" position, a holding circuit associated with said pick-up coil and controlled by said contactor for thereafter holding said relay picked up as long as said contactor coil circuit is energized, and braking means associated with said motor and connected to said contactor to be controlled by the latter to retard said motor during the delay interval of said relay, and an overload relay having a contact disposed in said contactor coil circuit for opening the latter in response to excessive overload current, said relay having a main coil connected with said motor to respond to said current and a lock-out coil for preventing said latter contact from reclosing when said lock-out coil is energized, said lock-out coil being connected to said master control means to be energized only when said master control means is in "hoist" and "lower" positions respectively.

7. A winch control system, comprising winch locking means, a winch motor, operator-actuable

master control means normally in "off" position and selectively adjustable to "hoist" and "lower" positions respectively, a contactor having a coil circuit controlled by said master control means to be energized when said control means is in one of said "hoist" and "lower" positions and having contact means controlled by said coil circuit, said master control means and said contact means being connected with said motor for operating said motor, when said coil circuit is energized, in different directions corresponding to the "hoist" and "lower" positions respectively of said master control means, a delayed drop-out relay connected to said locking means for releasing the latter when said relay is in picked-up condition, said relay having a pick-up coil connected with said master control means so as to be placed into pick-up condition only when said master control means is adjusted into "hoist" position, a holding circuit associated with said pick-up coil and controlled by said contactor for thereafter holding said relay picked up as long as said contactor coil circuit is energized, and braking means associated

with said motor and connected to said contactor to be controlled by the latter to retard said motor during the delay interval of said relay, braking means associated with said motor and controlled by said contactor to be effective during the delay interval of said relay in response to deenergization of said contactor coil circuit, and an overload relay having a contact disposed in said contactor coil circuit for opening the latter in response to excessive overload current, said relay having a main coil connected with said motor to respond to said current and a lockout coil for preventing said latter contact from reclosing when said lock-out coil is energized, said lock-out coil being connected to said master control means through said relay so as to be energized only when said relay is in picked-up condition while said master control means is in one of said "hoist" and "lower" positions.

KURT MAHNKE.
